UNITED STATES PATENT OFFICE.

HARRY SALMON AND HARRY BOOTON, OF WESTMINSTER, LONDON, ENGLAND,
ASSIGNORS TO THE EXPANDED METAL COMPANY, LIMITED, OF WEST-
MINSTER, LONDON, ENGLAND.

MACHINE FOR EXPANDING SHEET METAL.

1,408,647.

Specification of Letters Patent.

Patented Mar. 7, 1922.

Application filed August 27, 1920. Serial No. 406,424.

To all whom it may concern:

Be it known that we, HARRY SALMON and HARRY Booton, subjects of the King of Great Britain, residing at York Mansion, 5 York Street, Westminster, London, England, have invented new and useful Improvements in Machines for Expanding Sheet Metal, of which the following is a specification.

10 It has before been proposed to expand a slotted metal sheet by means of a machine having two divergent series of pairs of rollers or two diverging pairs of chains which grip the edges or selvages of the sheet and 15 feed them through the machine whilst compelling them to travel along divergent paths so that the sheet is expanded.

We have found that it is unnecessary to employ for gripping the selvages of the 20 sheet feeding or travelling means, such as rollers or chains.

According to this invention we employ a pair of fixed divergent guides each of which has throughout its length a slot along which 25 the selvages of the sheet can travel and which is provided with a shoulder behind which the up-turned selvage or extreme strand of the sheet engages so that the selvage cannot be pulled out of the slot, but must follow the 30 slot to the end of the guide. In some cases the sheet proceeds through the machine, as it leaves the slitting rollers and the rollers which displace the selvages out of the plane of the rest of the sheet, without any further 35 assistance, but in other cases we may provide at the further ends of the divergent guides a pair of pin wheels to engage the selvages of the expanded sheet and to draw it through the machine. The divergent guides may be 40 either straight or stepped in such a way that the central portion of the sheet is expanded first and that subsequently portions on each side of the centre are released from the guides and expanded successively.

45 In the accompanying drawings which illustrate the invention Figure 1 is a side elevation, Figure 2 is a plan thereof, Figure 3 is a side view showing the rolls, guides and expanded sheet, Figure 4 is a detail end view of 50 showing a sheet fully expanded, and pin wheels, and Figure 5 is a detail end view of the rolls for deforming the selvage. Figures 6, 7 and 8 are sections on the lines A—A, B—B, C—C, respectively, Figure 3,

Figures 5, 6, 7 and 8 all being to a larger 55 scale.

1 are selvage deforming rolls in bearings 14 and driven through spur wheels 15. Each roll has at one end an inwardly bevelled segmental flange 2 and at the other end a segmental flange 3 bevelled outwardly at the same angle as the flange 2, the flanges 2 and 3 of one roll being adapted to co-operate with the flanges 3 and 2 of the other roll.

When a metal sheet 4 which has previously been slotted in any suitable manner so as to form parallel strips connected by junctions of uncut metal is passed through the rolls 1, the selvages 5 are bent at intervals at right angles to the plane of the sheet 70 and are then also doubled or bent back in the opposite direction as is clearly shown in Figures 5 to 8.

After passing through the selvage rolls 1, the sheet 4 enters a guide 6 having in it a 75 slot 7 extending the width of the sheet 4, and a groove 8 at each end of the slot 7 along which the selvages 5 can travel.

On leaving the guide 6 the sheet 4 enters a pair of fixed divergent guides 9 each of 80 which is formed of a top and bottom plate arranged a suitable distance apart to form a slot 10 extending throughout its length along which the selvage 5 and part of the sheet 4 can travel; formed in the outer plate 85 of each guide 9 is a groove 11 the inner face of which forms a shoulder behind which the upturned selvage 5 of the sheet 4 engages so that the selvage cannot be pulled out of the slot 10 but must follow the slot 10 to the end 90 of the guide 9.

The guides 9 as shown in the drawings are tapered and have steps 90 along their inner edges and are at their wider ends adjacent to the selvage rolls 1 of such width that practically the whole of the sheet 4 is covered up or enclosed by the walls of the slots 10 so that only the central portion of the sheet 4 is expanded, portions on each side of the centre of the sheet being subsequently released from the slots 10 in the guides 9 and expanded successively until at the end of the guides the whole of the sheet 4 between the selvages 5 has been expanded, see Figures 3, 4, 7 and 8.

At the end of the guides 9 is arranged a pair of pin wheels 12 having chain wheels 120 driven by chains 13 actuated by chain

wheels 130 on the same axes as the selvage rolls 1. The pin wheels 12 engage the selvages of the expanded sheet 4 and draw it through the guides.

5 Though we prefer to use pin wheels 12 to draw off the sheet 4, these are not necessary.

What we claim is:—

1. In machines for expanding sheet metal, a pair of fixed divergent guides having 10 means adapted to engage each selvage of the sheet and enclose portions of the sheet in such a manner that only that part of the sheet which is not enclosed can expand, and means independent of the guides for forcing the sheet through the guides.

2. In machines for expanding sheet metal, a pair of fixed divergent and tapered guides having means adapted to engage each selvage of the sheet and enclose portions of the sheet 20 in such a manner that only that part of the sheet which is not enclosed can expand, and means independent of the guides for forcing the sheet through the guides.

3. In machines for expanding sheet metal, 25 a pair of fixed stepped divergent and tapered guides having means adapted to engage each selvage of the sheet and enclose portions of the sheet in such a manner that only that part of the sheet which is not enclosed can expand, and means independent of the guides for forcing the sheet through the guides.

4. In machines for expanding sheet metal, 35 a pair of divergent guides adapted to engage each selvage of the sheet and enclose portions of the sheet in such a manner that only that part of the sheet which is not enclosed can expand, and rolls adapted to deform the selvages and force the sheet 40 through the guides.

5. In machines for expanding sheet metal, a pair of divergent and tapered guides adapted to engage each selvage of the sheet and enclose portions of the sheet 45 in such a manner that only that part of the sheet which is not enclosed can expand, and rolls adapted to deform the selvages and force the sheet through the guides.

6. In machines for expanding sheet metal, 50 a pair of stepped divergent and tapered guides adapted to engage each selvage of the sheet and enclose portions of the sheet in such a manner that only that part of the sheet which is not enclosed can expand, and 55 rolls adapted to deform the selvages and force the sheet through the guides.

7. In machines for expanding sheet metal, a pair of divergent guides having grooves adapted to engage each selvage of the sheet 60 and enclose portions of the sheet in such a manner that only that part of the sheet which is not enclosed can expand, and means independent of the guides for forcing the sheet through the guides.

8. In machines for expanding sheet metal,

a pair of divergent and tapered guides having grooves adapted to engage each selvage of the sheet and enclose portions of the sheet in such a manner that only that part of the sheet which is not enclosed can expand, 70 and means independent of the guides for forcing the sheet through the guides.

9. In machines for expanding sheet metal, a pair of divergent guides having grooves 75 adapted to engage each selvage of the sheet and enclose portions of the sheet in such a manner that only that part of the sheet which is not enclosed can expand, and rolls adapted to deform the selvages and force the sheet through the guides.

10. In machines for expanding sheet metal, a pair of divergent and tapered guides having grooves adapted to engage each selvage of the sheet and enclose portions of the sheet 85 in such a manner that only that part of the sheet which is not enclosed can expand, and rolls adapted to deform the selvages and force the sheet through the guides.

11. In machines for expanding sheet 90 metal, rolls adapted to deform the selvages of the sheet, a guide having a slot extending the width of the sheet, and having grooves adapted to receive the selvages, and a pair of divergent and tapered guides having 95 grooves adapted to receive the selvages.

12. In machines for expanding sheet metal, rolls adapted to deform the selvages of the sheet, a guide having a slot extending the width of the sheet and having grooves 100 adapted to receive the selvages, and a pair of stepped divergent and tapered guides having grooves adapted to receive the selvages.

13. In machines for expanding sheet 105 metal, a pair of divergent guides having means adapted to engage each selvage of the sheet and enclose portions of the sheet in such a manner that only that part of the sheet which is not enclosed can expand, 110 means independent of the guides for forcing the sheet through the guides, and pin wheels adapted to engage the selvages of the expanded sheet.

14. In machines for expanding sheet 115 metal, a pair of divergent and tapered guides having means adapted to engage each selvage of the sheet and enclose portions of the sheet in such a manner that only that part of the sheet which is not enclosed can expand, 120 means independent of the guides for forcing the sheet through the guides, and pin wheels adapted to engage the selvages of the expanded sheet.

15. In machines for expanding sheet metal, 125 a pair of stepped divergent and tapered guides having means adapted to engage each selvage of the sheet and enclose portions of the sheet in such a manner that only that part of the sheet which is not enclosed can 130

expand, means independent of the guides for forcing the sheet through the guides, and pin wheels adapted to engage the selvages of the expanded sheet.

5 16. In machines for expanding sheet metal, a pair of divergent guides adapted to engage each selvage of the sheet and enclose portions of the sheet in such a manner that only that part of the sheet which is not enclosed can expand, rolls 10 adapted to deform the selvages and force the sheet through the guides, and pin wheels adapted to engage the selvages of the expanded sheet.

15 17. In machines for expanding sheet metal, a pair of divergent and tapered guides adapted to engage each selvage of the sheet and enclose portions of the sheet in such a manner that only that part of the sheet which is not enclosed can expand, rolls 20 adapted to deform the selvages and force the sheet through the guides, and pin wheels adapted to engage the selvages of the expanded sheet.

25 18. In machines for expanding sheet metal, a pair of stepped divergent and tapered guides adapted to engage each selvage of the sheet and enclose portions of the sheet in such a manner that only that part of the sheet which is not enclosed can expand, rolls 30 adapted to deform the selvages and force the sheet through the guides, and pin wheels adapted to engage the selvages of the expanded sheet.

35 19. In machines for expanding sheet metal, a pair of divergent guides having grooves adapted to engage each selvage of the sheet and enclose portions of the sheet in such a manner that only that part of the sheet which is not enclosed can expand, means independent of the guides for forcing the sheet 40 through the guides, and pin wheels adapted to engage the selvages of the expanded sheet.

45 20. In machines for expanding sheet metal, a pair of divergent and tapered guides having grooves adapted to engage each selvage of the sheet and enclose portions of the sheet

in such a manner that only that part of the sheet which is not enclosed can expand, means independent of the guides for forcing the sheet through the guides, and pin wheels 50 adapted to engage the selvages of the expanded sheet.

21. In machines for expanding sheet metal, a pair of divergent guides having grooves adapted to engage each selvage of the sheet 55 and enclose portions of the sheet in such a manner that only that part of the sheet which is not enclosed can expand, rolls adapted to deform the selvages and force the sheet through the guides and pin wheels 60 adapted to engage the selvages of the expanded sheet.

22. In machines for expanding sheet metal, a pair of divergent and tapered guides having grooves adapted to engage each selvage 65 of the sheet and enclose portions of the sheet in such a manner that only that part of the sheet which is not enclosed can expand, rolls adapted to deform the selvages and force the sheet through the guides, and pin wheels 70 adapted to engage the selvages of the expanded sheet.

23. In machines for expanding sheet metal, rolls adapted to deform the selvages of the sheet, a guide having a slot extending the 75 width of the sheet and having grooves adapted to receive the selvages, a pair of divergent and tapered guides having grooves adapted to receive the selvages, and pin wheels adapted to engage the selvages of the expanded sheet.

24. In machines for expanding sheet metal, rolls adapted to deform the selvages of the sheet, a guide having a slot extending the width of the sheet, and having grooves 85 adapted to receive the selvages, a pair of stepped divergent and tapered guides having grooves adapted to receive the selvages, and pin wheels adapted to engage the selvages of the expanded sheet.
